Term of patent 14 years

(Cl. D45—10)

To all whom it may concern:

Be it known that I, Benjamin Novgrad, a citizen of the United States, residing at Newington, in the county of Hartford, State of Connecticut, have invented a new, original, and ornamental Design for Finger Rings, of which the following is a specification, reference being had to the accompanying drawing, forming part thereof.

In the drawing:

Fig. 1 is a plan view of a finger ring embodying the design;

Fig. 2 is a view in side elevation of the ring looking from the right with reference to the position in which it is shown in Fig. 1;

Fig. 3 is a view in side elevation of the ring, looking from the left with reference to the position in which it is shown in Fig. 1;

Fig. 4 is a view in elevation of the ring looking in one direction substantially parallel with the axis of the finger opening; and

Fig. 5 is a view in elevation of the ring looking in the

The dominant feature of the design is that appearing in the solid lines.

I claim:

The ornamental design for a finger ring, as shown and described.
